UNITED STATES PATENT OFFICE.

LA FAYETTE MOORE, OF JACKSONVILLE, FLORIDA, ASSIGNOR TO L. MOORE
DRY KILN COMPANY, OF JACKSONVILLE, FLORIDA.

DRY-KILN.

No. 846,044.

Specification of Letters Patent.

Patented March 5, 1907.

Application filed October 4, 1906. Serial No. 337,486.

To all whom it may concern:

Be it known that I, LA FAYETTE MOORE, a citizen of the United States, residing at Jacksonville, in the county of Duval and State of Florida, have invented certain new and useful Improvements in Dry-Kilns, of which the following is a specification.

My invention relates to an improvement in dry-kilns, and has to do more particularly with improved trestle-work for the support of the rails inside of the kiln.

In Letters Patent No. 769,102, granted to me August 30, 1904, I illustrated a wooden trestle-work with two-by-four cross-beams for the support of the heating-pipes. Wooden trestle-work has a tendency to give way and scorch out in the course of one or two years constant use, so that frequent repairs become necessary in consequence.

My present invention contemplates the substitution of an iron trestle-work, which enables me to do away with all of the wood-work connected with the heating-surface in the dry-kiln, as supports and posting for the tracks, and while obviously there is a difference in cost of construction and installation my present construction of iron trestle-work has the decided advantage of greater durability, and this improved trestle-work when installed in a kiln will last as long as any portion of the kiln.

With these objects in view my present invention consists in certain novel features of construction and combinations of parts, which will be hereinafter described, and pointed out in the claims.

In the accompanying drawings, Figure 1 is a longitudinal section through the kiln, showing my improved trestle-work. Fig. 2 is a transverse section. Fig. 3 is a foundation plan of the structure. Fig. 4 is a top view. Fig. 5 is an enlarged perspective view of one of the posts, showing a cap, connecting-rods, and a section of a rail fastened thereon. Figs. 6, 7, 8, and 9 are details.

Referring to Fig. 5, A represents one of the posts, of which there are as many rows extending throughout the length of the kiln as there are rails to be supported. In the ordinary construction, as shown in Fig. 2, there are three of these rails 1-1. Obviously more or less might be employed, according to the size of the kiln and the character of stock to be handled. These posts or columns are

preferably made of two-inch piping, and 55 they take the place of the six-by-six wooden posting shown in my former patent. These posts or columns are mounted on bottom plates 2-2, and the latter are fastened to the four-by-eight timbers 3-3, which extend from 6c one end of the kiln to the other, these timbers preferably being supported on two-by-eight sills 4-4, which extend across the kiln from wall to wall 5-5, resting at intermediate points upon the piers 6-6.

A cap 7 is screwed or otherwise secured to the upper end of the posts, an enlarged view of one of these caps being shown in Fig. 6. Four lugs 8 depend from the edges of these caps, and each lug is provided with a hole 9, 70 adapted to receive the ends of the three-fourth-inch stay-rods 10-10, which latter extend transversely and longitudinally of the trestle-work, as shown in Fig. 4, the outer rod extending through the masonry of the 75 wall, where they are provided with washers and nuts for securing them rigidly at that point. In this way the posts or columns are rigidly braced from the top by means of a network of rods extending in four directions 80 from each post, whereby they are made to withstand all longitudinal and lateral strain, to which they are subjected by the heavy weight supported by the columns. The rails 11 are secured to these caps by means of 85 clips 12-12, which are held fast to the caps by bolts 13-13, passing through the holes 14 and 15 in the clips and caps, respectively.

While the foregoing trestle-work is applicable to any form of kiln, I have illustrated it in 90 connection with my own particular type of patent kiln, and therefore in this connection attention is especially called to the zigzag heating-pipes 16, 17, and 18, also shown in the patent referred to, but which it is a function of my present invention to provide for and support. These heating-pipes rest upon one and one-half inch cross-pipes 19-19, (see Fig. 2,) and these cross-pipes form an adjustable rack made adjustable by means of 100 the hooks 20-20, which are slipped over the two-inch posts or columns A-A, where they are held at the desired elevation by means of set-screws 21-21. In this way the hooks are quickly adjusted to the elevation which the 105 zigzag heating-pipes take, so that they are evenly supported throughout their length and throughout the length of the kiln.

From the foregoing it will be seen that I have provided a construction which comprises few, simple, and durable parts capable of being easily set up or replaced, as most of the parts are made in duplicate and can be mounted and rigidly braced by the exercise of ordinary mechanical skill. At the same time the construction is such that the entire trestle-work is of metal, and consequently as enduring as the masonry of which the entire kiln is built.

It is evident that slight changes might be resorted to in the form and arrangement of the several parts described without departing from the spirit and scope of my invention, and hence I do not wish to limit myself to the exact construction herein set forth; but,

Having fully described my invention, what I claim as new, and desire to secure by Letters Patent, is—

1. The combination with a post or column, of a cap having lugs, and stay-rods adjustably connected to the lugs.

2. The combination with a post or column for a trestle and a removable cap, of stay-rods, means for the adjustment of the stay-rods, and means for the support of a rail.

3. A trestle for kilns and the like, comprising a plurality of posts, caps secured thereto and stay-rods extending from one cap to another whereby to afford lateral support for bracing the posts.

4. The combination with a foundation and superstructure, of posts or columns, caps thereon and stay-rods extending radially in four directions from each cap, the outer ends of the outside stay-rods secured to the superstructure.

In testimony whereof I have signed my name to this specification in the presence of two subscribing witnesses.

LA FAYETTE MOORE.
